UNITED STATES PATENT OFFICE.

RUDOLPH STEINERT, OF NEW HAVEN, CONNECTICUT.

DESIGN FOR A PHONOGRAPH-NEEDLE.

55,097.

Specification for Design.

Patented May 4, 1920.

Application filed October 25, 1919. Serial No. 333,400. Term of patent 14 years.

To all whom it may concern:

Be it known that I, RUDOLPH STEINERT, a citizen of the United States, residing at New Haven, in the county of New Haven and State of Connecticut, have invented a new, original, and ornamental Design for Phonograph-Needles, of which the following is a specification, reference being had to the accompanying drawing, forming a part thereof.

In the drawings:—

Figure 1 is a side elevation of a phonograph needle showing my new design,

Fig. 2 is a bottom plan view of the needle shown in Fig. 1, and

Fig. 3 is a view end elevation looking from the left in Fig. 1.

I claim:

The ornamental design for a phonograph needle as shown.

RUDOLPH STEINERT.
